UNITED STATES PATENT OFFICE.

HARRY F. GEIST, OF RACINE, WISCONSIN, ASSIGNOR, BY MESNE ASSIGNMENTS, TO WEBSTER ELECTRIC COMPANY, OF RACINE, WISCONSIN, A CORPORATION OF WISCONSIN.

IGNITION MECHANISM FOR INTERNAL-COMBUSTION ENGINES.

1,308,235.

Specification of Letters Patent.

Patented July 1, 1919.

Application filed September 20, 1915. Serial No. 51,632.

To all whom it may concern:

Be it known that I, HARRY F. GEIST, a citizen of the United States, residing at Racine, in the county of Racine and State of Wisconsin, have invented a certain new and useful Improvement in Ignition Mechanism for Internal-Combustion Engines, of which the following is a full, clear, concise, and exact description, reference being had to the accompanying drawings, forming a part of this specification.

My invention relates to ignition mechanism for internal combustion engines, and particularly to that type of ignition mechanism wherein a magneto arranged to be driven by an associated engine is so connected and related to make and break contact mechanism located within the combustion chamber of the engine as to effect the operation of the electrodes forming a part of the contact mechanism and thus accomplish the passing of an electric spark at the proper instant in the cycle of engine operation.

The object of my present invention is to provide an ignition mechanism of this class that is capable of being economically manufactured, one wherein the operation of the make and break devices as well as the magneto rotor are positively and properly effected. Simplicity of construction is an essential feature of my present invention.

My invention is explained in detail in the following description wherein reference is made to the accompanying drawings, in which

Figure 1 is a view, partly in section and partly in elevation, illustrating the improved mechanism of my invention;

Fig. 2 is a view taken on the line 2—2 of Fig. 1 looking in the direction indicated by the arrows; and

Fig. 3 is an isolated elevational view of the electrodes which are disposed within the combustion chamber of the internal combustion engine with which the mechanism of my invention is associated.

Similar characters of reference refer to similar figures throughout the several views.

Referring first to Fig. 1, I have illustrated at 6 a bracket arranged to be secured to the wall of an associated internal combustion engine by bolts or other similar instrumentalities passing through apertures 7—7 formed in the plate 8 which is integral with

the aforesaid bracket 6. The bracket 6 comprises a horizontal shelf 9 upon which is mounted a magneto generator 10 which may be of any approved type; that is, either of the wound rotor type or of the unwound rotor type. The magneto rotor shaft illustrated at 11 is provided with a crank 12, the lower end of which engages in the bifurcated end of an arm 13 formed integral with a collar 14 keyed upon a shaft 15 extending through the bracket 6 to the wall of the associated internal combustion engine cylinder. The wall of the engine cylinder has been diagrammatically illustrated by dotted lines at 16. The collar 14 previously referred to is provided with a pair of diametrically opposite arms 17—17, each of which is connected by a spring 18 with an extension 19 of the bracket 6 and it will thus be seen that the springs 18—18 normally serve to retain the magneto rotor and the shaft 15 in the positions illustrated in Figs. 1 and 2. Carried by the left hand end of the shaft 15 (Fig. 1) is an arm 20 provided with an electrode 20^a. It will thus be seen that the electrode 20^a, the shaft 15 and the rotor shaft of the magneto are mechanically and positively connected for synchronous operation. Disposed around the shaft 15 is a unit comprising a plurality of sleeves of metal and insulating material and which unit bears in the bracket 6. The aforesaid unit comprises a metal sleeve 21 around which is disposed a sleeve 22 of insulating material. Disposed around the insulating sleeve 22 is a sleeve 23 of conducting metal which at the left hand end thereof (Fig. 1) is provided with an arm 24 carrying an electrode 24^a which is disposed in immediate proximity to but normally out of engagement with the electrode 20^a, as clearly illustrated in Fig. 3. The sleeve 25 of insulating material serves to insulate the sleeve 23 from the bracket 6 and the wall of the engine cylinder and another sleeve 26 is provided for the purpose of bearing against the walls of the bracket 6. It will be understood that the several sleeves disposed around the shaft 15 constitute one unit as before stated and that these sleeves rotate together. I may state at this point that the electrode 20^a is what may be termed the grounded electrode being grounded to the bracket through the springs 18—18, or by special conductors, if desired, and that the electrode 24^a is the

insulated electrode and is connected in the magneto circuit by a conductor connected with a suitable clip 27 which is in electrical engagement with the sleeve 23, as is illustrated in Fig. 1. Formed integral with the right hand end of the sleeve 26 (Fig. 1) is a depending arm 28 provided at its lower end with an adjustable screw 29 normally engaging a lug 30 carried by the shelf of the bracket 6. A spring 31 acting between the arm 28 and the bracket 6 normally serves to retain the arm 28 and parts connected thereto in the positions illustrated in Figs. 1 and 2.

15 The collar 14 which is disposed upon the right hand end of the shaft 15 (Fig. 1) is provided with a trip finger 32 arranged to be driven by an engine driven actuator, as, for instance, a reciprocating rod to move 20 the shaft 15 and parts connected therewith against the tension of the springs 18-18 and then release the finger, whereupon all of the parts connected with the collar 14 including the shaft 15 and the magneto rotor 25 shaft, are returned to normal position. The general construction and mode of operation of engine driven actuators of the type mentioned are commonly known and, therefore, I have thought it unnecessary to illustrate 30 such a device in the present disclosure.

The mode of operation of the magneto just described is as follows:

35 The trip or push finger 32 is moved in a contraclockwise direction (Fig. 2) against the action of the springs 18-18 thereby moving the magneto rotor and the electrode 20^a inasmuch as both of these parts are mechanically connected with the push or trip finger. When the electrode 20^a is so moved, 40 it is brought into engagement with the electrode 24^a inasmuch as the electrode 24^a is disposed in the path of the electrode 20^a. After the electrode 20^a engages its associated 45 electrode 24^a and continues to move under the action of the engine driven actuator, it carries the electrode 24^a with it against the action of the spring 31, which normally tends to hold the electrode 24^a in the position illustrated in Figs. 1 and 3. When the 50 trip finger 32 is released from the engine driven actuator, the springs 18-18 serve to quickly move the electrode 20^a and the rotor of the magneto toward their normal positions and the spring 31 returns the electrode 24^a toward its normal position. The 55 electrodes 20^a and 24^a remain in engagement with each other until the screw 28 comes into engagement with the lug 30 (Fig. 2). When this occurs, further movement of the electrode 60 24^a is prevented and separation of the electrodes occurs. It will be understood that the adjustment of the several parts is such

that separation of the electrodes occurs at the instant when the peak of the current wave induced within the magneto windings is attained. This operation is repeated to produce a spark at the proper instant in each cycle of the internal combustion engine to accomplish the necessary ignition of the charge in a well known manner.

65 Attention is directed to the fact that the magneto of my invention hereinbefore described is removably mounted upon its associated supporting bracket and that the ignition devices may, if desired, be operated without the magneto to produce ignition sparks, provided the electrodes are connected in circuit with a suitable source of current, as, for instance, a battery.

70 Having thus described my invention, what I claim as new and desire to secure by Letters Patent of the United States is:

1. In combination with an internal combustion engine, a framework secured to the engine cylinder, a shaft bearing in the framework, a pair of electrodes within the cylinder one of which is mounted on said shaft, a magneto removably supported by the framework having the rotor thereof detachably connected with said shaft, means 85 connected with the shaft arranged to be engaged by an engine driven member to oscillate the shaft and rotor together with spring means positively connected with said shaft whereby said shaft is incapable of movement except in opposition to said spring means, said spring means arranged quickly to return the shaft and parts connected therewith to normal to effect the operation 90 of the electrodes and generate a current in the magneto when the shaft is oscillated by the engine driven member and released.

95 2. A magneto igniter mechanism comprising a plug, a pair of make and break electrodes, a shaft extending through said plug having one of said electrodes carried on the inner end thereof, a yoke carried by the outer end of said shaft, fixed with respect thereto, and incapable of movement independently thereof, spring means acting between said yoke and a member fixed with respect to said plug, together with means for moving said yoke and shaft in opposition to said spring means, and for tripping said yoke and shaft, and means for detachably 100 connecting said shaft with the rotor of a magneto generator.

105 In witness whereof, I hereunto subscribe my name this 18th day of September, A. D. 1915.

HARRY F. GEIST.
